DUPLICATING ATTACHMENT FOR
TYPEWRITERSThomas H. Clarkson-Jones, Toronto, Ontario,
Canada

Application December 14, 1933, Serial No. 702,304

3 Claims. (Cl. 197—126)

This invention relates to devices employed to take the place of the usual sheets of carbon paper in duplicating typewritten copies, and particularly to that form in which a strip of transfer material is carried by a thin frame supported on the side frames of a typewriter. With such devices as at present arranged it is only possible to use a narrow band, or, at most, two out of the whole width of the strip. Further there is always left unused the transfer material of the strip which falls between successive letters or words. My object therefore is to devise means for utilizing a very much larger proportion of the transfer material of the strip than is now possible, thus increasing the useful life of a strip.

I attain my object by so supporting the frame carrying a transfer strip that it is simultaneously movable both longitudinally and transversely of the typewriter platen by means actuated by the platen or platen turning mechanism of the typewriter, the movement being stepwise and reversing each time the predetermined limit of movement in one direction or another is reached.

The invention is hereinafter more fully described and is illustrated in the accompanying drawings in which—

Fig. 1 is a front elevation of one form of the device, partly broken away, and showing parts of a typewriter;

Fig. 2 a plan view of parts of the same;

Fig. 3 a plan view of parts of the typewriter concerned with the invention;

Fig. 4 a detail in side elevation of parts shown in Fig. 3;

Fig. 5 a detail in plan of a modification;

Figs. 6 and 7 sectional plan views showing the construction of a transfer slip and its connection to a duplicator frame;

Fig. 8 a front elevation of a second modification;

Fig. 9 a side elevation of the same;

Fig. 10 a front elevation, broken away, of parts of a typewriter and duplicator frame illustrating means for causing a movement of the frame in one direction to also actuate it in a direction at right angles to the first;

Fig. 11 a front elevation of a third modification;

Fig. 12 a side elevation of the same;

Fig. 13 a detail of the right and left hand threaded screw shown in Figs. 11 and 12 and the parts connected therewith.

In the drawings like numerals of reference indicate corresponding parts in the different figures.

Referring particularly to Figs. 1 to 4 of the drawings, 1 is part of the frame of a typewriter and 2 the platen thereof. 3 is a duplicator frame of thin metal, which is of U-form, and to the lower ends of which are secured the ends of the transfer slip 4. This transfer slip may be a narrow typewriter ribbon, but is preferably formed of a strip of ordinary carbon paper. This strip is shown in plan in Figs. 6 and 7, from which it will be seen that the ends of the slip are thickened so that the ends slightly spread the sheets of paper between which the strip is interleaved so as to relieve pressure on the thinner active part of the strip to prevent it being dragged when the paper is shifted relative thereto in preparation for the duplicating of a fresh line of the copy.

The frame 3 is supported on the supports 5, which are connected with the frame of the typewriter at each end. These supports carry the pins or rollers 6, which project through diagonal slots 7 formed in the frame 3.

From the construction described it follows that, if the frame 1 be pushed either endwise or vertically, the transfer slip 4 will be shifted simultaneously endwise and vertically. To effect such a movement of the frame 3 I provide the cam 11, which cam is pivoted on the bracket 10 secured to the typewriter frame. Rotatable with the cam is the ratchet wheel 12, with which engages the pawl 14 pivoted on the slide 13, which is suitably guided on the bracket 10. The cam 11 engages one end of the frame 3, so that as the cam is rotated the frame is pushed endwise to the limit of the throw of the cam. The frame at the same time moves up and down, as hereinbefore referred to.

The slide 13 is provided with the depending fork 15, which engages the slide 8, which is a part of the typewriter mechanism in common use for imparting a stepwise rotary movement to the platen. This slide is actuated by the lever 9 when the operator desires to shift the platen to start a fresh line of typing. Consequently, every time the platen is operated the cam is rotated a distance equal to one or more teeth of the ratchet wheel 12 and a stepwise rotary movement is thus imparted to the cam, which, in turn, imparts a stepwise movement to the frame 3, and thence to the transverse slip 4. By this means the transverse slip is so moved that practically every part of its active surface may be utilized for duplicating purposes.

While gravity may be employed to effect the return movement of the frame 3, I prefer to employ a flat bent spring 16 connected to the

typewriter frame at one end, which spring tends to maintain the frame 3 in its extreme left-hand position, which is, of course, also its lowest position.

5 In Fig. 5 I show a modification in which the cam 11^a and the ratchet wheel 12^a are mounted on a horizontal spindle. The cam surface of the cam is necessarily therefore formed on its side and not on its periphery. The mode of operation of the ratchet wheel 12^a may be substantially as in the form shown in Fig. 1.

10 In Figs. 8 and 9 I show a modification of the construction shown in Figs. 1-4. In this form the cam 11^b rests directly on and is driven by the platen 2. The cam is journaled in a slide 17 positioned within a housing formed by the bracket 10^b. This slide is guided by the fork 18 formed at its lower end which embraces the spindle of the platen, and also by the stem 19 which passes 20 through the top of the housing 10^b. A coil spring engages the slide 17 and the top of the housing 10^b and serves to press the cam into close contact with the platen. A frame holder 20 is connected with the slide 17 and serves to support one or 25 more frames 3, as indicated in Fig. 9. The frame or frames, when in place, are held in position by the pivoted latch 21, which may be swung from the position shown in full lines in Fig. 9 to a position to release the frame. One complete set 30 of the parts just described is employed at each end of the platen, so that the frame 3 is simultaneously lifted at each end. The simultaneous endwise movement of the frame 3 may either be by means such as shown in Fig. 1 or by such 35 means as are illustrated in Fig. 10.

It will be noted that an inclined plane 23 is formed on one end of the duplicator frame 3 and an opposed inclined plane 24 on a part secured to the typewriter frame 1. As the parts ride up and 40 down over one another, when the frame 3 is moved up and down, the frame is moved endwise, the movement to the left being imparted by the flat bent spring 16 secured to the opposite side of the typewriter frame 1 and bearing against 45 the frame while the movement to the right is caused by the downward riding of the surface 23 over the surface 24.

In Figs. 11 and 12 a further modification is shown. In this form also the primary movement 50 imparted to the frame is up and down and the endwise movement may be arranged for either as by the inclined slots and pins of Fig. 1 or by the arrangement illustrated in Fig. 10 previously described. In the present modification a frame

25 is secured to the typewriter and in it is journaled the screw 26, which is formed with a right-and-left hand reversing thread of known type adapted to actuate the slide 27. To the lower end of the spindle of the screw is secured the pinion 5 28 which bears against the end of the platen 2 so that the screw is rotated as the platen turns. As will be readily understood, the continued rotary movement of the screw imparts a rectilinear reciprocating movement to the slide 27 through 10 the medium of the journaled pin 26. To the slide 27 is secured the frame holder 20, provided with the latch 21, these parts being similar to those hereinbefore described with references to Figs. 8 and 9 of the drawings. One of these 15 devices is necessarily employed at each end of the platen.

From the above description it will be seen that I have devised apparatus which will satisfactorily attain the objects of my invention as set out 20 in the preamble to the specification.

What I claim as my invention is:

1. The combination with a typewriter provided with a platen of a frame carrying a transfer strip; inclined guiding means for the said frame 25 such that an endwise movement of the frame is accompanied by a movement transversely of the platen; a cam rotatably mounted on the typewriter and bearing against the frame for effecting such motion; and means for effecting a step- 30 wise rotary movement of the said cam comprising a ratchet wheel adapted to rotate the cam, a slide, and a pawl carried by the slide and engaging the ratchet.

2. The combination with a typewriter provided 35 with a platen of a frame carrying a transfer strip; inclined guiding means for the said frame such that an endwise movement of the frame is accompanied by a movement transversely of the platen; and means on the typewriter for effecting 40 such motion comprising a slide engaging the frame; a right-and-left hand threaded screw actuating the slide; and a pinion on the screw rotatable by the typewriter platen.

3. The combination with a typewriter provided 45 with a platen of a frame carrying a transfer strip; inclined guiding means for the said frame such that an endwise movement of the frame is accompanied by a movement transversely of the platen; means on the typewriter for effecting 50 such motion; and a spring tending to return said frame to its initial position.

THOMAS H. CLARKSON-JONES.
